[57] CLAIM

The ornamental design for a sliding gate, as shown.

DESCRIPTION

FIG. 1 is a front elevational view of a sliding gate in the extended position thereof, showing my new design;

FIG. 2 is a front-elevational view of the sliding gate in the retracted position thereof;

FIG. 3 is a top plan view of the gate in the position of FIG. 1;

FIG. 4 is a rear-elevational view of the gate in the position of FIG. 1;

FIG. 5 is a right-end elevational view of the movable portion of the gate; and

FIG. 6 is a left-end elevational view of the movable portion of the gate.

FIG. 4

FIG. 6

FIG. 5
